WINDOW DISPLAY DEVICE

Luther G. Simjian, Riverside, Conn.

Application December 7, 1937, Serial No. 178,475

15 Claims.

(Cl. 40—52)

This invention relates, generally, to the displaying of goods in store windows and the like, and the invention has reference, more particularly, to a novel window display device adapted for 5 enabling a relatively large quantity of goods to be viewed through a relatively small window.

In high rent areas, the tendency is to reduce the size of store fronts so that the store windows thereof are very limited in area, with the result 10 that but few goods can be displayed at a time, which is highly objectionable inasmuch as the necessary inducement for bringing customers into the store is not present.

The principal object of the present invention 15 is to provide a novel window display device that serves, in effect, to convert a limited store window opening space into a multiple window opening space, so that a storekeeper having a small store frontage can exhibit his goods on the scale 20 of a multiple store front window system.

Another object of the present invention lies in the provision of a novel window display device of the above character that is adapted to show the goods individually and without the necessity of 25 moving the same.

Still another object of the present invention is to provide means for exhibiting a projected description of the goods to be displayed, on a screen, so that the customer will know in advance what 30 the next item to be displayed is going to be, together with the price thereof, etc.

Still another object of the present invention is to provide a lighting arrangement whereby each 35 item to be displayed is most favorably illuminated, the lights and shadows being most suitable for exhibiting the item.

Other objects and advantages will become apparent from the specification, taken in connection with the accompanying drawings wherein 40 the invention is embodied in concrete form.

In the drawings,

Fig. 1 is a plan view, partly in section, of the novel window display device of the present invention.

Fig. 2 is a sectional view taken along line 2—2 of Fig. 1.

Fig. 3 is an enlarged fragmentary, sectional view taken along line 3—3 of Fig. 1.

Fig. 4 is a sectional view taken along line 4—4 of Fig. 1.

Fig. 5 is a view similar to Fig. 2, illustrating a slight modification of the invention.

Fig. 6 is a wiring diagram.

Fig. 7 is a sectional view in elevation of a somewhat modified form of the invention.

Similar characters of reference are used in all of the above figures to indicate corresponding parts.

Referring now to Figs. 1 to 4, the reference 60 numeral 1 designates a store or other window, be-

hind which goods are to be displayed, said window being normally of somewhat small area so that but few goods could be displayed behind the same in the ordinary manner. The window space immediately to the rear of window 1 is shown as 5 divided into two shallow display compartments 2, 3 and a central deep compartment or passage 4 extending quite some distance to the rear of window 1. At the open sides of compartment or passage 4 there are provided a plurality of additional display compartments 5 to 12, inclusive, within which goods are adapted to be displayed, facing toward the central compartment 4.

A movable carriage 13, having wheels 14, is 15 movable along tracks 15, 15' that extend along the length of the compartment 4. A vertical mirror 16 has upper and lower trunnions 38, 38' pivotally mounted upon the carriage 13 for turning about a vertical axis so that the face of the mirror may be positioned at 45° with respect to 20 the longitudinal axis of compartment 4, whereby a person looking in through the window 1 may directly observe articles in compartments 5 to 12 by reflection from the mirror 16. In Fig. 1, the mirror is shown positioned for displaying the 25 goods in compartment 9. Lamps 17 are illustrated as installed upon the carriage 13 for illuminating the compartments 5 to 12, these lamps being provided with suitable reflectors 17' for 30 directing the light most favorably upon the goods displayed.

In order to move the carriage 13 along the tracks 15, 15', a motor 18 is provided. This motor is connected through worm and wheel reduction gearing 19 to a Geneva gear 20 having the driving pin 21 for operating in the slots, such as 34 and 35, of the cross member 20' of the gear. The cross member 20' is fixed upon a shaft 22 that is connected through spur gearing 23 for driving a sprocket shaft 24 having a sprocket 24' thereon 40 driving the sprocket chain 25 extending longitudinally within compartment 4 and passing around an idler sprocket 26 at the forward portion of this compartment. The carriage 13 is connected to be driven by sprocket chain 25, as 45 by a rod 27 pivoted at its lower end as upon one of the pivotal pins of the sprocket chain, the said rod being adapted to slide vertically in a guide bearing 28 provided on the carriage 13, as the same passes around the sprockets 24', 26. Thus, 50 as the motor 18 operates continuously in one direction, the Geneva gear 20 serves to drive the sprocket chain 25 so that carriage 13 is reciprocated in an intermittent manner forwardly and rearwardly within the compartment 4. The gear 55 ing is such that the carriage comes to rest opposite each of the compartments 5 to 12, i. e., during the stationary periods of the Geneva cross member 20'.

In order that a description of the goods about 60

to be exhibited in each successive compartment may be given the prospective customers looking through window 1, a motion picture projector 30 is shown mounted upon the carriage 13 at the rear thereof. In order that the projected picture produced by projector 30 may be seen from in front of the window 1, the silver on mirror 16 is divided into narrow vertical strips that are mutually spaced from one another, i. e., this mirror 10 is half silvered, thereby allowing the picture projected upon the back of this mirror to be seen from in front of window 1. The projector 30 is operated while the carriage 13 is in motion, so that as this carriage moves from one compartment to the next, the desired information is projected by the projector.

In order to control the operating motor 31 of the projector, suitable switching means is provided, operated from the Geneva gear 20. Thus, 20 as shown in Fig. 6, the drive pin 21 of this gear is arranged to operate levers 32 and 32' of a start-stop switch 33 having the projection motor 31 in the circuit thereof.

In operation, assuming the carriage to be in 25 the position shown in Fig. 1, the mirror 16 is disposed for displaying the goods in compartment 9, the Geneva gear drive pin 21 having just moved out of the lower radial slot 34 of Geneva cross member 20' (see Fig. 4). While the goods 30 are being thusly displayed, the pin 21 continues to move around until it enters the right hand upper slot 35 of cross member 20', thereupon starting to turn the gear 20' and effect rearward movement of the carriage 13. Just as the pin 35 21 commences to enter the slot 35, it actuates lever 32 of switch 33, thereby causing the energization of film motor 31 and the deenergization of lamps 17 so that during the rearward movement of the carriage from the position opposite the compartment 9 to the position opposite the compartment 10, the projector is in operation, describing the goods which are about to appear in compartment 10. On arriving opposite compartment 10, the drive pin 21 has turned slot 35 downwardly into the position of slot 34 shown in Fig. 4, and on leaving this slot, actuates the switch arm 32' to effect the deenergization of motor 31 and the illumination of lamps 17 so that the objects within the compartment 10 are readily viewed from in front of window 1.

After an interval, dependent upon the speed of motor 18, the carriage will again be moved rearwardly into a position opposite compartment 11, during which movement the projector 30 will operate to inform the customer of the qualities, prices, etc. of the goods within this compartment.

Still later, the carriage will arrive opposite the compartment 12. After leaving compartment 12, the carriage will move rearwardly somewhat while the rod 27 passes upwardly around the rear sprocket 24', and while thus moving rearwardly, a lever arm 36 on mirror trunnion 38' is engaged and actuated by a stationary pin 37 positioned within the chamber 4, this pin serving to turn the mirror 16 upon carriage 13 from the full line position shown in Fig. 1 through 90° to the dotted line position shown therein, in which position the apparatus is ready for viewing the goods in compartment 8. While the rod 27 was moving rearwardly around the sprocket 24', the projector 30 was also operating to inform the customer or observer of the nature of the goods in compartment 8.

Continued operation of drive motor 18 now causes the carriage 13 to be advanced step by step from compartment 8 to compartment 5, displaying successively the goods in the compartments 5 to 8, while the pin 27, actuating the carriage, is connected to the upper run of sprocket chain 25.

After exhibiting the goods in compartment 5, the rod 27 moves forwardly somewhat and down around the sprocket 26, and in so doing, causes 10 a pin 37' in compartment 4 to actuate the lever 36 and turn mirror 16 through 90° to its full line position preparatory to viewing the goods in compartments 9 to 12. Thus, the operation of the display device is continuous and entirely automatic, the projector serving to give information of the nature of the goods in each compartment prior to the actual arrival of the carriage opposite such compartment, and upon the arrival of the carriage thereat, the projector is 20 shut off and the lights 17 illuminated for displaying the goods.

In this way a large volume of goods may be displayed when only a relatively small show window is available.

If desired, instead of operating the moving picture projector 30 while the carriage is moving from one compartment to another, a curtain or shade 39 may be operated by a shade motor 40 (see Fig. 5) to block off the compartment 4 during such movement of the carriage, in which case the entire surface of mirror 16 is silvered. This shade motor 40 in such case would be connected to switch 33 in lieu of motor 31, as shown in Fig. 6. Upon the deenergization of the motor 40, the spring in the winding drum 41 of the shade would automatically withdraw the shade upwards so as to expose the compartment 4 to view.

In some instances it may not be desired to utilize much space to the rear of the window for display purposes, as in Fig. 1, but it may be preferable to utilize space vertically for this purpose, as shown in Fig. 7. The apparatus in this figure is very similar to that of the preceding figures and corresponding parts are correspondingly numbered, with the exception that the carriage 13 is shown as moving vertically instead of horizontally and a permanent inclined mirror 42 is positioned to the rear of the window 1'. Thus, a prospective customer, by looking through the window 1', will see the goods in compartments 5' to 12' successively displayed. It would appear that further description of this form of the invention would be unnecessary.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It will be obvious that instead of using a plurality of display compartments at each side of passage 4, but a single display compartment may be used at each side of this passage, and if desired, the carriage 13 may be moved with a continuous instead of an intermittent motion. Also, the projector 30 may be mounted in a stationary position, as above the path of travel of the carriage, and may project upon the shade 39, if desired, in which case this shade could be made translucent, it being understood that this shade is connected as by straps or cords to motor 40 for operation by the latter.

What is claimed is:

1. In a display device, a plurality of display compartments, and a mirror movable from compartment to compartment for reflecting the 5 contents thereof for purposes of observation.
2. In a display device, means providing a viewing passage with compartments opening upon said passage, a mirror within said passage, and means for moving said mirror in intermittent 10 steps along said passage so that the same comes to rest opposite each compartment for use in viewing the contents thereof.
3. In a display device, means providing a viewing passage with compartments opening upon 15 said passage, a mirror within said passage, means for moving said mirror in intermittent steps along said passage so that the same comes to rest opposite each compartment for use in viewing the contents thereof, and means for orienting 20 said mirror, whereby the same is suitably positioned for reflecting the contents of each compartment.
4. In combination, a show window and a display device therewithin, said device comprising a 25 passage, compartments disposed along the sides of said passage, a carriage movable along said passage, and a mirror mounted on said carriage for reflecting the contents of said compartments along said passage for observation from in front 30 of said show window.
5. In combination, a show window and a display device therewithin, said device comprising a passage, compartments disposed along the sides of said passage, a carriage movable along said 35 passage, a mirror mounted on said carriage for reflecting the contents of said compartments along said passage for observation from in front of said show window, motive means for moving said carriage whereby the latter is brought to rest opposite each compartment, and means for turning said mirror, whereby the contents of the 40 compartments on both sides of said passage are selectively viewed.
6. In a window display device, means providing a passage with compartments opening upon 45 said passage, a half silvered mirror within said passage, means for moving said mirror in intermittent steps along said passage whereby the same comes to rest for an interval opposite each compartment for reflecting the contents thereof along said passage, and a projection apparatus 50 movable with said mirror and operable during such movement to project through said mirror and along said passage information as to the contents of said compartments.
7. In a window display device, means providing a passage with compartments opening upon 55 said passage, a half silvered mirror within said passage, means for moving said mirror in intermittent steps along said passage whereby the same comes to rest for an interval opposite each compartment for reflecting the contents thereof along said passage, a projection apparatus movable with said mirror and operable during such 60 movement to project through said mirror and along said passage information as to the contents of said compartments, and switching means for stopping the operation of said projection apparatus while said mirror is at rest opposite a compartment.
8. In a display device for use in store windows, means providing a passage, a plurality of compartments facing upon opposite sides of said 65
- passage, a carriage movable along said passage, a mirror mounted on said carriage for reflecting the contents of said compartments along said passage, a motor drive for moving said carriage, and intermittent gearing included in said motor drive for temporarily arresting the movement of said carriage as said mirror arrives opposite each compartment. 5
9. In a display device for use in store windows, means providing a passage extending within the 10 store from the window, a plurality of compartments facing upon opposite sides of said passage, a carriage movable along said passage, a mirror mounted on said carriage for reflecting the contents of said compartments along said passage, a motor drive for moving said carriage, intermittent gearing included in said motor drive for temporarily arresting the movement of said carriage as said mirror arrives opposite each compartment, and means for turning said mirror 15 with respect to said carriage at the limits of travel of said carriage, whereby said mirror enables the viewing of the compartments on both sides of said passage. 20
10. In a display device, means providing a 25 viewing passage with compartments opening upon said passage, a mirror within said passage, means for moving said mirror in intermittent steps along said passage so that the same comes to rest opposite each compartment for use in 30 viewing the contents thereof, and a shade operated in synchronism with said mirror for closing off the view to said passage during movement of said mirror.
11. In a display device, a plurality of display 35 compartments, a mirror movable intermittently from compartment to compartment for reflecting the contents thereof for purposes of observation, lamps movable with said mirror for illuminating said compartments, and means for energizing said lamps during the periods that said mirror is at rest adjacent said compartments. 40
12. In a display device, a plurality of display compartments, a mirror movable from compartment to compartment and having a period of 45 rest at each compartment, a picture projector and lamps movable with said mirror, and means for operating said picture projector during the periods of movement of said mirror and for energizing said lamps during periods of rest of 50 said mirror.
13. In a display device, means providing a passage, a display compartment opening upon said passage, and a mirror movable along said passage and having its face extending at an angle to the length thereof for projecting an image of the contents of said compartment along said 55 passage.
14. A display device as defined in claim 13, wherein a second mirror is positioned so as to intercept said image and to reflect the same to a desired point for observation. 60
15. In a window display device, means providing a passage with compartments opening upon said passage, a mirror within said passage, means for moving said mirror in intermittent steps along said passage whereby the same comes to rest for an interval opposite each compartment for reflecting the contents thereof along said passage, and a projection apparatus operable during such movement to project information as to the contents of said compartments. 65
